CEMENT SPRAYER

Irwin R. Henderson, Charleston, W. Va.

Application April 16, 1938, Serial No. 202,564

4 Claims. (Cl. 166—19)

This invention relates to cement sprayers which are tools used by the well drilling industry for the purpose of directing films of fluid cement against the walls of wells at points where there is a tendency to cave, thereby reinforcing the wall.

Various means for this purpose have been devised but have generally been objectionable because the force of the discharging stream or streams of liquid cement has tended to bore into the walls and break them down faster than the healing or solidifying effect of the cement could be attained.

Tools heretofore used have also been objectionable because it has been difficult to release the cement at the proper point or points.

An object of the present invention is to provide a simple and efficient tool which can be lowered readily to a predetermined point and, while being supported at said point, can be actuated to release the liquid cement.

A further object is to provide a tool which will deliver the liquid in a conical sheet which is unbroken and serves to engage the wall throughout its circumference, thereby avoiding the objectionable results where the liquid is delivered in jets against the wall.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

In the accompanying drawings the preferred form of the invention has been shown.

In said drawings:

40 Figure 1 is a side elevational view.

Figure 2 is a vertical longitudinal section therethrough, the valve being shown locked in closed position.

Figure 3 is a similar view showing the valve open and liquid being sprayed therefrom.

Figure 4 is an enlarged section on line 4—4 of Figure 2.

Figure 5 is an enlarged section on line 5—5 of Figure 2.

50 Referring to the figures by characters of reference 1 designates the head of the tool which is preferably cylindrical and has a reduced neck portion 2 extending upwardly therefrom. A longitudinal recess 3 is formed in this head and in the neck portion and has an inlet opening 4

in the wall thereof for the reception of a plug 5 adapted to slide longitudinally within the recess 3. This plug has a tapered opening 6 extending therethrough and seated therein is the end portion 7 of an operating cable 8, said end portion being held in the plug by means of Babbitt metal or the like indicated generally at 9.

As the upper end of the recess 3 is reduced in diameter to provide an annular shoulder 10, said shoulder constitutes a stop for limiting the relative sliding movement of the plug 5 and the head 1.

Extending downwardly from recess 3 through the bottom of head 1 is a bore 11, the upper portion of which is enlarged or counterbored as at 15 12. A radial passage 13 opens into this counterbore from the outer side of the head and is intersected by a longitudinal guide channel 14 in the outer surface of the body.

A tripping slide 15 is mounted in this channel 20 and has a groove 16 in one side thereof in which is seated a stop screw 17 which is fastened to the head 1 and serves to hold the cover strip 17' in the channel 14. This cover strip terminates at the shoulder 18 formed by head 1 at the base of neck 2 but the tripping slide 15 extends beyond this shoulder and normally projects above the neck as shown in Figures 1 and 2.

The lower end of the tripping slide 15 is formed with a downwardly and inwardly beveled deflecting surface 19 and this lower end portion of the slide is adapted to extend through a slot 20 formed within a latch 21 which is slidable in the radial opening 13. One wall of the slot 20 is beveled, as shown at 22. Slot 20 and slide 15 are 30 so proportioned that when the beveled face 19 of the slide is located in slot 20, the beveled face 22 of the slot 20 can be moved inwardly against face 19 a sufficient distance to allow the inner end of the latch 21 to extend into the bore 12 as shown 35 40 in Figure 2.

A tubular casing 23 of any suitable length is secured to and extended downwardly from the head 1, this casing being formed preferably of a metal tube, the upper end of which extends 45 around and is fastened to the lower end portion of the head. The lower end of the tubular casing 23 extends around and is secured to a sleeve 24 the upper end of which is preferably flared as at 25 while its lower end portion is also flared as at 50 26 to form a valve seat.

An opening 27 is formed in casing 23 near its upper end. Slidably mounted in the bore 11 is a valve stem 28 having a cylindrical head 29 at its upper end which is slidable in counter-bore 12 55

and has an annular groove 30. To the lower end of this stem is secured a valve 31 having a conical base 32 adapted to fit snugly against the flared seat 26, said valve being also formed with a cylindrical portion 33 above the conical surface which will seat snugly in the sleeve 24.

The parts are so proportioned that when the valve 31 is fitted against its seat 26 so as to close the lower end of sleeve 24, the annular groove 30 in head 29 is located to receive the latch 21 so that the valve is thus held in closed position. Before the latch can be moved into the groove it is of course necessary to thrust the tripping slide 15 upwardly to the position shown in Figure 2.

A weight 34 is slidably mounted on the cable 8 but is normally raised off of the tool herein described.

In practice a fluid mixture of cement and water is poured into the casing 23 through the opening 27 after the valve 31 has been locked in closed position. The tool is then lowered into the well W until its lower end is brought to a position where there is a tendency to cave. The tool is then held suspended at this point after which the weight 34 is released and permitted to slide downwardly along the line 8 until it comes against the tripping strip 15. Impact against this strip will cause the strip to slide downwardly so that its deflecting surface 19 will thrust against the inclined wall 22 of latch 21. Consequently the latch will be thrust radially from the counter-bore 12 and out of the annular groove 30. This will result in the release of stem 28 and the weight of the supported fluid will cause valve 31 to move downwardly to open position. Thus there will be formed an annular conical outlet and the supported liquid will instantly flow outwardly in a conical sheet against the adjacent portions of the wall of the well which will be thoroughly sprayed.

After all of the contents of the tool have been discharged, the tool is raised from the well, the valve reseated and locked, and another charge of liquid placed in the casing 23. The tool is then ready to be again used in a manner heretofore described.

Importance is attached to the fact that the liquid is delivered from the tool in an unbroken conical sheet which serves thus to be distributed throughout the circumference of the adjacent

portion of the well wall. Thus there is no tendency of the discharging liquid to tear down the wall, as would be the case if the liquid be delivered in jets.

What is claimed is:

1. A cement sprayer including a casing having a conical valve seat at its lower end, a conical valve cooperating with the seat to retain a fluid cement in the casing, a latch for holding the valve to the seat, a supporting line for the casing, a weight slidable along the line, and means operated by the weight for actuating the latch to release the valve to deliver an unbroken, conical sheet of fluid cement between the valve and seat. 5

2. A cement sprayer including a casing for holding fluid cement or the like, said casing having a conical valve seat at its lower end, a conical valve, a latch for holding the valve to its seat to support the fluid in the casing, a supporting line for the casing, a weight slidable along the line, 10 and means operated by the weight for actuating the latch to release the valve and free the supported fluid in an unbroken conical sheet. 15

3. A cement sprayer including a casing having a valve seat for holding fluid cement in the casing, said casing having a flared valve seat at its lower end, a conical valve, a latch for holding the valve to its seat to support the fluid in the casing, a supporting line for the casing, a weight slidable along the line, and means operated by 25 the weight for actuating the latch to release the valve and free the fluid from the casing, said seat and valve cooperating to deliver the fluid in an unbroken conical sheet. 30

4. A cement sprayer including a casing having a flared valve seated at its lower end, a head at the upper end of the casing, a line connected to the head for supporting the sprayer, a conical valve normally engaging the seat, a stem thereon slidable in the head and having an annular latch 40 receiving portion, a radially movable latch in the head for engaging the stem to hold the valve in closed position, a tripping element slidable along the head and within the latch, said latch and element having cooperating deflecting bases, and means movable along the line and against said tripping element to shift the latch out of engagement with the stem and release the valve from its seat. 45

IRWIN R. HENDERSON.
